UNDERWATER DRILLING METHOD

Arthur E. Wilde, Santa Ana, Calif., assignor to Shaffer Tool Works, Brea, Calif., a corporation of California Filed Apr. 22, 1958, Ser. No. 730,172 4 Claims. (Cl. 166—46)

This invention relates to a method for drilling bore holes in the earth and relates more particularly to apparatus and method for underwater drilling of such holes in the production of wells such as oil wells and the like.

While the invention has particular utility in connection with offshore drilling of oil wells and the like, and is herein shown and described in connection therewith, it is to be understood that its utility is not limited thereto.

In the prior art, wells have been drilled into submarine formations in relatively shallow water protected to some extent at least by reefs or the like. Also, in some prior operations various types of structures have been employed to support the equipment required to drill the well, including platforms and the like.

Where the water is shallow, the problems of offshore or underwater drilling are not difficult of solution. However, there are many difficult problems involved in drilling in deep water and in certain localities such as the Pacific Coast for example, the waters are relatively deep even a short distance from shore.

When the drilling is in such relatively deep water, a floating platform is used and comprises a specially equipped boat or barge which must be anchored as securely as possible. Various problems are encountered from the initial drilling operations to the completion of the well and the installation of the production equipment.

It is, therefore, an object of the present invention to provide means and method for solving these problems.

In the drilling operations, the well head and blowout preventer equipment should be mounted as close to the underwater floor as possible and it is another object of the invention to provide means located close to the ocean floor for remotely connecting the various equipment to the casing or disconnecting said equipment from said casing.

It is another object of the invention to provide improved means and method for initiating the drilling operations.

It is a further object of the invention to provide improved means for effecting the cementing operations.

It is a still further object of the invention to provide effective means for supporting one or more strings of tubing.

It is another object of the invention to provide means for releasably securing the tubing hangers.

It is a further object of the invention to provide means and method for lowering and connecting various tools to the mandrel at the upper end of the installed casing.

It is still another object of the invention to provide means and method for raising and lowering various tools.

The characteristics and advantages of the invention are further sufficiently referred to in connection with the following detailed description of the accompanying drawings which represent a preferred embodiment of the method and apparatus or means. After considering this example, skilled persons will understand that many variations may be made without departing from the principles disclosed and I contemplate the employment of any structures, arrangements or modes of operation that are properly within the scope of the appended claims.

Referring to the drawings:

FIG. 1 is a perspective undersea view of a boat used in connection with the present invention;

FIG. 2 is a side view, partially in section of the anchor

2

in place and the drill pipe with the drill just beginning to drill into the formation;

FIG. 3 is a sectional view of the conductor with the landing base and bucket and swabs for cementing, and cement guide;

FIG. 3A is a sectional view of the cable bucket showing the J slot therein;

FIG. 4 is a side elevation, partially in section, showing the drilling and setting packer and drilling string stabbed therethrough;

FIG. 5 is a side elevation, partially in section, of the equipment used in the fifth stage of the drilling operations;

FIG. 6 is a side elevation, partially in section, of the equipment used in the sixth stage of the drilling operations;

FIG. 7 is a side elevation, partly in section, of the succeeding or seventh stage of the drilling procedure;

FIG. 8 is a side view, partially in section, of the last or eighth stage of the drilling operations;

FIG. 9 is a side view, partially in section, of the upper end of the well head equipment fully installed;

FIG. 10 is a side view, partially in section, of the lower portion of the well head equipment installed;

FIG. 11 is a side view of the setting tool for bit guide with the bit guide attached thereto;

FIG. 12 is a similar view showing the bit guide installed and the setting tool drawn upwardly therefrom;

FIG. 13 is a fragmentary longitudinal section of a portion of the well head equipment showing the bit guide in position; and

FIG. 14 is a side view of a final release rod assembly.

Referring to FIG. 1, underwater drilling operations are carried out from a floating support or boat, as disclosed in the Gibson et al. application, Serial No. 627,250, for Method and Apparatus for Offshore Drilling, filed December 10, 1956. The boat, indicated generally at 25, is anchored, by cables 26, over the formation into which the well is to be drilled. Boat 25 is provided with the usual machinery and equipment for drilling wells and includes a derrick 27 disposed over an opening or well 28 which extends vertically through the ship and through which equipment is raised and lowered and the drilling operations carried out.

The boat is provided with the various equipment required for drilling operations and in FIGS. 1 and 2 there is shown a drill string 30 having a rotary drill at the lower end thereof, indicated schematically at 31.

Preparatory to the drilling operation itself, an anchor 35 is lowered onto the surface 36 of the formation 37 into which the well is to be drilled or bored. The anchor is of substantial weight and is shown as comprising a reinforced block of concrete 38 having a relatively large central opening 39 therethrough and also having a downwardly extending peripheral flange 40 which penetrates the surface of the formation. The anchor remains in position because of its weight and is held from shifting by reason of said weight and also the flange 40.

Guide cables 42 have their lower ends secured by any suitable well-known clamp means to respective pins 43 mounted in the upper ends of members 44 projecting above the top surface of the anchor. The members 44 have their lower parts securely embedded in the anchor 38 or otherwise secured thereto. The cables 42 extend upwardly through the well 28 and are attached at their upper ends to torque converters which maintain said cables taut as described in the above referred to Gibson et al. application, Serial No. 627,250.

The vertical opening 39 through the anchor 35 is of substantial cross sectional area and is of substantially

greater diameter than the diameter of the upper end of the well to be drilled.

After the anchor 35 has been lowered on to the surface 36 of the formation 37 by means of the guide cables 42, the drill string 30 is assembled with the drill 31 at the lower end and the latter is guided downwardly by means of a bit guide, indicated generally at 50. The bit guide includes a ring 51 which is slidable on the drill collar 52 which carries the bit 31 at its lower end. Bit guide 50 also includes a pair of oppositely extending arms 53 having tubular cable receiving elements 54 in which the guide cables 42 are slidable. During the bit lowering procedure, the ring 51 rests on the shoulder 56 of the bit 31. When the bit enters the opening 39, the elements 54 contact the ears 44 and thereafter the collar 52 slides downwardly through the ring 51. As the drilling continues, the drill string, of course, continues to slide through said ring 51. The first portion 57 of the well is bored and it is to be noted that the bit guide 50 guides the bit substantially axially through the opening 39.

After the bore portion 57 has been drilled to the desired depth, the drill string 30 and bit 31 are removed and as the bit rises above the surface of the anchor 35, it picks up the ring 51 and is guided to the boat.

Next the casing 60, FIG. 3, is assembled and a manila rope tied to the lower end, the free end portions of the rope then being tied to the respective guide cables 42 with a loop 62 of sufficient size to permit ready sliding thereof on said cables. The casing is lowered and thus guided into the bore 57.

At the upper end of the casing 60, there is a landing base assembly which comprises a plate 63 of larger size than the opening 39 in the anchor 35. Plate 63 is connected to the upper end of a tubular part 64 a little larger than the casing 60. Plate 63 may be welded to the part 64 or otherwise secured thereto and there are reinforcing plates 65 beneath the plate 63 and the tubular part 64. Plates 65 are welded or otherwise secured to the plate 63 and tubular part 64 and said plates 65 are arranged vertically. The lower end of the tubular part 64 is connected to the upper end of the casing 60 by any suitable means such as screw threads or by welding. As shown, there is an enlarged diameter part 66 in the lower end of the tubular part 64 in which is received an upper end portion of the casing 60. The parts are then welded together. Spaced upwardly of the upper end of casing 60 are a plurality of vent openings 67 in the tubular part 64 and spaced upwardly from said vent openings is an interior annular shoulder 68 in said tubular part 64.

The tubular part 64 has an enlarged external diameter portion 69 which extends upwardly of the plate 63 and to which is secured a cable bucket 70 that is funnel shaped with the large open end facing upwardly. There are a pair of arms 73 which extend oppositely of each other from the bucket and the part 69 of the tubular part 64 and have at their outer free ends tubular sliding elements 74 having vertical openings therethrough in which the cables 42 are slidable. The upper end of the casing with its landing base assembly is thus guided downwardly by means of said cables, string 30 being used to lower the casing.

For the cementing operation, there is provided a pair of swabs 80 attached in the usual manner to the lower end of a drill pipe section 81. The upper end of the pipe section 81 is threadably or otherwise secured to the lower end of a sub 82 connected at its upper end to the lower end of the drill string 30. The sub 82 has secured thereto a cylindrical member 83 having a flange 84 at its upper end, the lower end of said flange being downwardly and inwardly inclined to form a seat 85. The external diameter of the member 83 is such as to readily but snugly enter into the upper ends of the tubular part 64. Member 83 has a pair of oppositely arranged pins 86 for entry into the upper open ends 87 of J-slots 88 arranged diametrically within the portion 69 of the tubular part 64,

as best shown in FIG. 3A. When pins 86 reach the lower end of the vertical portion 89 of the J-slot 88, the drill string and member 83 are rotated to cause the pins 86 to move into and through the horizontal part 90 of said slot and into the inner vertical portion 91 and thence to the lower end of said inner vertical portion. When well pressure is exerted upwardly on the swabs 80, the pins 86 will move into the upper end of the slot portion 91 and the swabs thus held securely in the well. The member 83 has a plurality of vertically arranged annularly spaced fins 93 which are secured to the sub 82 and also to said member for reinforcement purposes. It is to be noted that the lower ends of the fins 93 are rounded to facilitate entrance thereof into the upper end of the tubular part 64.

When the member 83 is disposed as shown in FIG. 3, the swabs 80 are disposed somewhat below the vent openings 67. Cement then is introduced into the well through the drill string 30 and passes upwardly in the annulus 95 about the casing. The cement is indicated at 96 and it is to be noted that it does not rise completely to the surface 36. After the cementing operation has been completed, the drill string is rotated to effect removal of the pins 86 from the slots 88 and the string with its swabs 80 is removed. It is to be noted that when lowering the swab 30 into the well, a guide arrangement such as shown at 50, FIG. 1, may be used to align said swabs with the bucket 70 and open upper end of the tubular part 64. As the swabs are removed, they pick up the guide and the latter stabilizes the lower end of the drill string 30 as it is raised to the ship.

The next step in the drilling procedure is the drilling of a reduced diameter bore 100, FIG. 4, for the surface pipe, said bore 100 being drilled to any desired depth.

Preparatory to drilling the bore 100, the drill string is prepared with a drill collar 101 at the lower end and a drill 102 at the lower end of said collar. Above said collar there is disposed a drilling and setting packer assembly which includes a tubular body 105 at the lower end of which is attached by screw threads or the like, an inflatable packer, indicated generally at 106. This packer is of known type and includes an upper cylindrical member 107 which is of somewhat smaller external diameter than the internal diameter of the tubular part 64 and casing or conductor pipe 60. At the upper end of the cylindrical member 107 is an enlarged diameter part having a downwardly facing seal 108. The cylindrical member 107 has a passage 109 therethrough and depending from said member is a reduced diameter portion 110 on which is disposed a seal element 112 of suitable resilient material such as a synthetic rubber or the like which will not be affected by the fluids and other materials it will come into contact with. The seal 112 has an annular recess 114 which provides a fluid pressure chamber and said seal is secured onto the reduced diameter portion 110 by a nut 115 which is threadably attached to the lower end of said portion 110. Chamber 114 is connected to a suitable source of hydraulic pressure by a conduit 116 which is connected to a passage through the member 107, the latter being connected to said chamber 114 by means of a passage 117.

At the upper end of the tubular body 105, there is attached, by screw threads or other suitable means, a rotary submarine drilling head 120 of suitable character, having a rotatable seal therein which is engageable with the drill string. Examples of such drilling heads are disclosed in the above referred to Gibson et al. application, Serial No. 627,250. There are oppositely extending arms 122 on the drilling head 120 and said arms are provided at their outer ends with tubular sliding elements 123 for slidably reception therein of the guide cables 42.

When the drill string is initially lowered from the boat or floating support, the lower end of the inflatable packer 106 rests upon the shoulder 124 of the bit 102 inasmuch as the passage through said packer is of smaller internal diameter than the external diameter of the collar 101.

However, it is to be understood, that the internal diameter of the passage through said packer is large enough to permit free rotation of the collar and drill string therein. Thus, the entire assembly of packer 106, body 105 and rotary drilling head 120 is supported by the drill bit 102 as the latter is lowered into the well and the guide arrangement, including the arms 122 and elements 123, guide the bit and packer into the housing 70 and thence into the upper end of the part 64 of the landing base assembly.

When the seat 108 of the inflatable packer 106 seats on the shoulder 68 of the tubular part 64, the drill bit 102 continues on downwardly but the above referred to packer, body and drill head assembly is supported in the position shown in FIG. 4. Hydraulic pressure is then supplied to the chamber 114 to expand the seal 112 into tight sealing engagement with the interior of the conductor pipe or casing 69 and the tubular part 64. This prevents drilling fluid and the like from escaping upwardly into the water past said packer. Such drilling fluid however flows upwardly between the drill string and the wall of the interior passage of the packer 106, the passage through the tubular body 105 and into the head 120. The rotatable seal in the head provides a seal against escape of fluid past the drill string and into the water. The drilling fluid leaves the head by means of the valve arrangement indicated generally at 125 which is provided with a body 127 and a discharge or outlet conduit 128. Any suitable arrangement may be employed for taking off the fluid, there being devices of this character on the market. For example, the Cameron "Flex-Seal" mud valve may be used.

After the packer 106 has been inflated into sealing engagement with the interior of the well casing, the drilling of the bore 100 proceeds. When this bore has been drilled to the desired depth, it is raised by means of the drill string 30 which includes a bumper sub 129. The pressure to the packer having been relieved so that the seal 112 returns to its normal external diameter, the assembly of said packer 106, body 105 and head 120 will be raised by said drill string when the shoulder 124 of the bit 102 engages the lower end of said packer.

Reference is now made to FIG. 5 for the fifth stage in the drilling procedure. A casing or surface pipe 135 is assembled and lowered into the bore 100. The lower end of the casing 135 is guided downwardly on the cables 42 by means of the manila rope arrangement described above, the loops of said rope being shown at 137 in FIG. 5. At the upper end of said casing or surface pipe, there is provided a safety release joint of suitable character, indicated generally at 136, interior details being shown in FIGS. 9 and 10. Joints of this character are also disclosed in the Waggener application, Serial No. 390,321, for Torque Releasing, Safety Joint for Well Tool Strings, filed November 5, 1953, the Waggener application, Serial No. 605,241 for Release Casing Safety Joint for Well Tool Strings, filed August 21, 1956 and the McClintock et al. application, Serial No. 648,293 for Hydraulic Release Safety Tool Joint, filed March 25, 1957. This safety release joint includes a tubular mandrel 138 of such external diameter as to be slidably received in the portion of the tubular part 64 above the shoulder 68 thereof, said mandrel having an inwardly and downwardly inclined seat 139 adapted to seat on said shoulder 68, the lower end of said mandrel being connected by screw threads or other suitable means to the upper end of the casing 135 and the latter is supported thereby. The mandrel also has a depending portion 140 of somewhat reduced diameter to be received within the portion of the tubular part 64 below said shoulder 68 thereof. The part 140 terminates above the openings 67 and there is a depending reduced diameter part 142 to which is threadably or otherwise connected a collar 143 which in turn is threadably or otherwise connected to the upper end of the casing 135. The collar 143 is of somewhat smaller external diameter than the internal diameter of the tubular part 64, to permit passage

of fluid upwardly between said part 143 and the interior of the part 64, and there is an annular space or recess 144 between the lower end of the part 140 of the mandrel and the upper end of the collar 143, with which space 144 the ports or openings 67 communicate.

The release joint 136 also includes a barrel unit, indicated generally at 145 (FIGS. 5 to 10 and 13). Referring more particularly to FIGS. 9 and 10, the barrel unit includes a tubular barrel 146 having a tubular sub 147 connected to the upper end, the latter being connected to the bottom of a dual blowout preventer, indicated generally at 150, FIG. 5.

The mandrel 138 has an upwardly extending reduced diameter portion 151 slidably receivable in the lower end 15 of the barrel 146 and provided with helical or inclined recesses 152 for reception of lugs 153 on the inner side of the barrel. There is also a key sleeve 154 slidable within the barrel and urged to a predetermined lower position by a spring 155. When the lugs 153 are 20 in the recesses 152, keys 156 on the lower end of the key sleeve 154 enter key recesses 157 to prevent the lugs 153 from moving upwardly and outwardly of the recesses 152. Thus, the barrel unit is securely held on the mandrel but may be released therefrom by a releasing tool as described in said Waggener application, Serial No. 605,241.

Referring to FIG. 5, there is shown a spool connector 160 connected to the upper end of the dual blowout preventer in the usual manner. The connector 160 has a plurality of tapped openings therein whereby outlet valves 30 161 may be connected with the interior passage of said connector and also valves 162 may be connected with said passage. The upper end of the spool connector 160 is connected in the usual way to a blowout preventer indicated at 164. The blowout preventer 164 may be of 35 any suitable type, one such type being disclosed in the above referred to Gibson et al. application, Serial No. 627,250 and manufactured by the Hydril Company and identified as their Type G-K. Secured to the upper end of the blowout preventer 164 is a submarine drilling head 40 165 also disclosed in the above referred to Gibson et al. application, Serial No. 627,250 and in the Gibson et al. application, Serial No. 670,428 for a Drilling Head, filed July 8, 1957. Attached to the upper end of the rotary submarine drilling head 165 is secured, by any suitable 45 well-known means, a cable bucket or funnel 166 similar to the cable bucket 70. Arms 167 on the bucket have cable receiving elements 168 for slidably reception of said cables. There are a pair of support rods 169 having end members 170 and 171. The members 170 are pivotally connected at 50 172 to the arms 167 and the members 171 are pivotally connected at 173 to bosses 174 on the blowout preventer 150. A turnbuckle 175 is provided for each support rod for adjusting the length thereof.

The blowout preventer 150 is of well-known type and 55 includes upper and lower rams 176 and 177 respectively. Rams 176 are shown in the closed position wherein they are received within an external peripheral groove in a tool 178. The upper end of tool 178 is connected to the adjacent end of the drill string 30 and the lower end of said tool is connected to a section of drill pipe 180 having a pair of swabs 80 attached adjacent the lower end thereof and spaced longitudinally apart.

Lowering of the equipment shown in FIG. 5 is accomplished in the manner described in the above referred to 60 Gibson et al. application, Serial No. 627,250. The rams 176 of the preventer 150 are closed into the groove in tool 178 to thereby connect said preventer to said tool and hence to the string 30. The equipment above the blowout preventer 150 is, of course, carried thereby as well as the safety release joint 136 and the casing 135. 65 When the equipment is in the position shown in FIG. 5, with the shoulder 139 of the release joint 136 seated on the shoulder 68, the rams 176 are opened by supplying pressure fluid through one of the conduits 183 to the hydraulic actuating mechanism of said rams. As dual hy- 70 75

draulic blow-out preventers such as shown at 150 are known in the art, it is believed that it is unnecessary to describe their construction in detail.

With the equipment positioned as shown in FIG. 5, cement is supplied through the drill string and discharged therefrom below the swabs 89. The cement passes downwardly in the surface pipe 135 and upwardly about the same in the bore 100. Cement also passes upwardly between the exterior of said surface pipe and the interior of the conductor pipe where these pipes are telescoped together at the upper end. The cement flows upwardly into the recess 144 and out of the openings 67 into the upper end of the bore 57.

After the cementing operation has been completed, the swabs are raised and the stripper sleeve assembly 190, FIG. 6, of the rotary drilling head 165 is released by supplying hydraulic pressure through one of the conduits 191 connecting the drilling head 165 with a source of suitable hydraulic pressure. As described in the Gibson et al. application, Serial No. 670,428, the stripper sleeve assembly is released by hydraulic latching and releasing means. As the swabs are raised, they engage and pick up the released stripper sleeve assembly which is carried to the ship.

The sixth stage, FIG. 6, is the drilling of a further reduced diameter bore 200 from the lower end of the bore 100, said bore 200 being drilled to any desired depth. Preparatory to drilling bore 200, the drill string is assembled with a bumper sub 202 at the lower end thereof and a drill collar 203 at the lower end of said bumper sub with the bit 201 at the lower end of said collar. The stripper sleeve 190 is disposed on the string and is supported on the shoulder 204 of the bit as the latter is lowered. Above the stripper sleeve is disposed a guide, indicated generally at 205, comprising a ring 206 having a central opening sufficiently large to slide on the bumper sub 202 and drill collar 203. The ring is provided with outwardly extending arms 207 which carry the cable receiving element 208 in which the cables 42 are slidably disposed. As the bit is lowered through the submarine drilling head 165, blowout preventer 150 and down into the well, the stripper sleeve assembly enters the head 165 and seats therein. Thereafter, hydraulic pressure is supplied through the appropriate conduit 191 to effect locking of the sleeve in the head. As in the case of the head 120, there is a seal that engages the drill string and is rotatable in the head so as to rotate with said string during the drilling operations. Drilling fluid is circulated through the well during the drilling operation for the bore 200 as in the case of the drilling operation for drilling the bore 100. Also, it is to be understood that a blowout preventer 164 is interposed between the spool connector 160 and the drilling head 165, said blowout preventer 164 being omitted from the assembly shown in FIG. 6.

After the drilling of the bore 200 to the desired depth, the drill is removed, the stripper sleeve assembly being released from the drilling head 165 by supplying hydraulic pressure to the releasable latching mechanism of said head 165 and the stripper sleeve assembly and guide 205 are carried upwardly on the bit 201.

A casing string 210, FIG. 7, of the proper size for the bore 200 is then assembled and lowered into the well. The lower end of the casing string 210 is provided with a rope guide arrangement such as described hereinabove in connection with the casing 60 and casing 135. The rope arrangement guides the lower end of the casing into the well. At the upper end of the casing 210 there is connected, by means of a collar 211, a self-locking tubing or casing hanger, indicated generally at 214, FIG. 10, which is disclosed in the Gibson application, Serial No. 508,615 for Self-Locking Tubing Hanger, filed May 16, 1955. This tubing hanger has an external annular seat 215 that tapers downwardly and inwardly and seats on an internal annular shoulder 216 in the mandrel 138 of the safety release joint 136. The tubing hanger is provided

with latch means which includes a plurality of annularly arranged resilient fingers 217 having free end portions 218 which are releasably received in an internal annular groove 219 in said mandrel 138 in upwardly spaced relation to the shoulder 216 of said mandrel. The upper end of the automatic tubing hanger 214 is provided with an upwardly extending externally threaded portion 220 on which is screwed an adapter 221 which is provided at the upper end with a socket 222 having left-handed release threads 223. Within the adapter 221 there is an annular shoulder 224 and an internal groove 225 spaced upwardly therefrom. A left-hand back off tool 226 is provided at the lower end of the string of pipe used for lowering the casing 210 with its automatic hanger 214 and adapter 221. When the casing 210 has been installed and cemented in, the back off tool is removed in the usual manner and raised to the boat.

This is followed by the seventh stage of the drilling operations, a further reduced diameter bore 230 being drilled from the lower end of the bore 200, the bore 230 being drilled with equipment and according to the procedure described hereinabove. After bore 230 has been drilled to the desired depth, the drilling equipment is removed to the boat.

In the eighth stage a casing string 235 is assembled and the lower end thereof provided with a rope guide arrangement such as described above in connection with other casing strings, said rope guide means guiding the lower end of the casing 235 into the bucket 70 and upper end of the well. The upper end of the casing 235 is connected by a collar 236 to a tubing hanger 237 of proper size, said tubing hanger 237 having an external annular seat 238 which tapers downwardly and inwardly and seats on the shoulder 224 of the adapter 221. The tubing hanger 237 includes the latch arrangement having fingers 217a with projections 218a which are releasably received within the annular groove 225 of said adapter 221.

The body portion 240 of the hanger 237 also serves as the mandrel of a safety release joint indicated generally at 241, said body portion 240 having a shank which extends upwardly and is provided with the spiral lug receiving recesses 153 and key slots 157 for reception of keys 156 of key sleeve 154 which is slidably mounted in the barrel 242 of the barrel unit, indicated generally at 243. The barrel unit 243 is, of course, connected to a pipe string extending upwardly to the boat. When the casing 235 has been lowered into position, at which time the seat 238 of the hanger 237 is seated on the shoulder 224, the casing 235 is cemented in and the barrel unit then removed from the mandrel portion of said safety release joint.

In order to prevent damage to the drill or parts of the well head, a casing safety joint bit guide is used, said guide being shown in FIGS. 11 and 12. The bit guide comprises a tubular body 250 adapted to be received on the upper end portion 251 of a mandrel shank 151, the lower end of said body resting on shoulder 252 of the mandrel. At the upper end of the body the bit guide flares outwardly and upwardly at 253 and at the upper end of the flared portion 253 there is an annular flange 254. Within the flange 254 are J-slots which are arranged at diametrically opposite sides and are adapted to receive respective pins 255 of a bit guide setting tool, indicated generally at 256. The lower end of the bit guide is rounded at 257 to facilitate ready reception thereof in the flange 254, said rounded portion 257 being at the bottom of a cylindrical portion 258 from which the pins 255 extend radially outwardly. The cylindrical portion 258 depends from a body portion 259 of said bit guide setting tool and is of somewhat smaller diameter. The body portion 259 of said setting tool tapers upwardly to a collar 260 which is connected to the lower end of a pipe string.

The bit guide is attached to the setting tool as shown

in FIG. 11. In attaching the bit guide, the pins 255 are inserted in the open ends of the vertical portion 262 of the J-slots and when said pins are at the lower ends thereof, the bit guide is rotated so that said pins pass through the horizontal portions 263 of said slots. When the pins enter the inner vertical portions 264 of said slots, the guide is lowered so that said pins enter the upper ends of said portions 264 which upper ends are above the horizontal portions 263 so that the bit guide will be locked on the setting tool. The bit guide should be attached by hand to prevent shearing off of the pins 255.

The assembly of bit guide and setting tool is turned to the left by hand and lowered so that the bit guide is disposed on the upper end of the mandrel as described above. As the unit is lowered over the mandrel, it will continue to be free turning to the left until the keys 250a in the bit guide body 250 engage with the key slots on the safety joint mandrel, at which time a build-up in torque resistance will indicate such engagement. It will be noted that the pins 255 have entered the lower portions of the vertical slot parts 264 which are below the horizontal parts 263.

At this point the setting tool is ready to be detached from the bit guide. Left-hand torque is again applied by using hand tongs or the like. The unit is raised slowly while holding the left-hand torque and the pins 255 of the setting tool will rotate into the horizontal portions of the J-slots of the bit guide until said pins reach the vertical portions 262 of said slots whereupon the setting tool will separate from the bit guide.

The bit guide may be readily removed by reattachment of the setting tool so that the pins 255 are inserted into the J-slots and moved to the position shown in FIG. 11 whereat said pins are in the upper ends of the portions 264 of said slots. The bit guide may then be removed from the mandrel and the assembly raised to the surface or to the boat. Bit guides of suitable size may be used in the various drilling stages to protect the equipment.

Preparatory to installing the production equipment, the dual blowout preventer 150 and the equipment above same are removed by disconnecting the barrel unit 146 from the mandrel 138 of the release joint 136. In order to effect release of said barrel unit, a special releasing tool is used in view of the fact that the upper end of the mandrel of the release joint 241 extends upwardly of the plane of the internal annular groove 270 in the key sleeve 271 of barrel unit 146.

The releasing tool for effecting release of the barrel unit 146 from its mandrel 138 is shown in FIG. 14. The device comprises a cylindrical body 275 which is open at the lower end and the cylindrical interior 276 of said body is adapted to slide over the above referred to mandrel. Adjacent the lower end of the body 276 are a plurality of vertically arranged annularly spaced openings 277 in which fingers 278 respectively are received. These fingers are pivoted at 279 adjacent their lower ends and the upper ends are urged outwardly by leaf springs 280 secured to the inner side of the body 275 by rivets 281 or the like. Each finger is provided with a leaf spring 280 and the upper ends 282 of said fingers are adapted to engage the shoulder 284 at the upper end of the recess 270. The body 275 is connected to a sub 285 which, in turn, is connected to a tubular portion 286, the latter being connected to an axially arranged tubular part 287 having at its upper end radial vanes 288 which serve to stabilize the tool and maintain it in proper axial arrangement within the barrel unit 246. The upper end of the tubular part 287 is provided with a collar 288a for connection with a string of pipes leading to the ship. When the tool has been lowered into position so that when the fingers 278 engage the shoulder 284, the key sleeve 271 will be pulled upwardly to remove the keys 156 from their slots 157. The lugs 153 will then slide out of their grooves 152 and the barrel unit will thereupon be separated from the mandrel.

In raising the dual blowout preventer and the equipment supported thereby the tool 178 is again employed and the rams 176 close into the groove provided in said tool. The entire assembly may then be raised by means of the drill string 30.

It is to be noted that removal of the blowout preventer 150 and the equipment supported thereby is effected in the manner described in the above referred to Gibson et al. application, Serial No. 627,250. In said Gibson application, the releasing tool for the barrel unit is of a different type from that shown in FIG. 14. However, the general mode of operation of the two arrangements is substantially the same.

The releasing tool is raised with the barrel unit, the blowout preventer 150 and the equipment supported thereby and is removed from the barrel after said barrel, blowout preventer and equipment has been raised to the ship.

After the preventer 150 and the other equipment has been raised, suitable means is attached to the last inserted casing of the well to conduct fluid therefrom to a point of disposal or collection.

It is thought that the invention and many of its attendant advantages will be understood from the foregoing description and it is thought that it will be apparent that various changes may be made in the form, construction and arrangement of the parts of the invention and the steps of the method thereof, without departing from the spirit and scope of said invention or sacrificing all of its material advantages.

I claim:

1. A method for drilling into an underwater formation, including the steps of: depositing an anchor on the surface of the formation, said anchor having an opening therethrough and having guide means attached to the anchor and extending to a surface support; assembling a pipe string on the support; securing the lower end of the pipe string to the guide means; lowering the pipe string along the guide means through the hole in the anchor to the surface of the formation; drilling a hole in the formation under the anchor; removing from said hole the pipe string; assembling a conductor casing; attaching a breakable link between the lower end of the casing and the guide means; lowering the casing to the surface of the formation; breaking the link; lowering the casing into the hole and cementing the casing in the hole.

2. A method for drilling into an underwater formation, including the steps of: depositing an anchor on the surface of the formation; said anchor having an opening therethrough and having guide means attached to the anchor and extending to a surface support; assembling a pipe string on the support; securing the lower end of the pipe string to the guide means; lowering the pipe string along the guide means through the hole in the anchor to the surface of the formation; drilling a hole in the formation under the anchor; removing from said hole the pipe string; assembling a conductor casing; attaching a breakable link between the lower end of the casing and the guide means; lowering the casing to the surface of the formation; breaking the link; lowering the casing into the hole; cementing the casing in the hole, guiding tools downwardly along the guide means into the hole; drilling the hole deeper; installing additional casing strings in the holes and securing a conduit to the last installed casing for conducting fluid therefrom.

3. A method for drilling into an underwater formation, including the steps of: depositing an anchor on the surface of the formation; said anchor having an opening therethrough and having guide means attached to the anchor and extending to a surface support; assembling a pipe string on the support; securing the lower end of the pipe string to the guide means; lowering the pipe string along the guide means through the hole in the anchor to the surface of the formation; drilling a hole in the formation under the anchor; removing from

said hole the pipe string; assembling a conductor casing; attaching a breakable link between the lower end of the casing and the guide means; lowering the casing to the surface of the formation; breaking the link; lowering the casing into the hole; cementing the casing in the hole; drilling the hole deeper; inserting additional casing strings in the preceding casing; suspending said additional casing on the preceding casing and securing a conduit to the last installed casing for conducting fluid therefrom.

4. A method for drilling into an underwater formation, including the steps of: depositing an anchor on the surface of the formation; said anchor having an opening therethrough and having guide means attached to the anchor and extending to a surface support; assembling a pipe string on the support; securing the lower end of the pipe string to the guide means; lowering the pipe string along the guide means through the hole in the anchor to the surface of the formation; drilling a hole in the formation under the anchor; removing from said hole the pipe string; assembling a conductor casing; attaching a breakable link between the lower end of the casing and the guide means; lowering the casing to the surface of the formation; breaking the link; lowering the casing into the hole; cementing the casing in the hole, assembling a drill string on the support; attaching a breakable link

5

25

between the lower end of the string and the guide means, lowering the string to the surface of the formation, breaking the link; lowering the string into the hole; drilling the hole deeper and removing the drill string from the hole.
